SURVEYING UNDERGROUND STRUCTURES

Benjamin B. Weatherby, Tulsa, Okla., assignor
to Geophysical Research Corporation, New
York, N. Y., a corporation of New Jersey

Application October 27, 1934, Serial No. 750,276

9 Claims. (Cl. 181—0.5)

In the method of surveying underground structures commonly known as the seismic method, artificial seismic waves are created by detonating a charge of explosive at or near the earth's surface and the travel times of the reflected and refracted waves to points distant from the wave source are measured by means of suitable wave-receiving and recording apparatus. The explosive charge usually is placed at the bottom of a drilled 5 hole which may be located from 10 to 150 feet in depth. It has been found that the character of wave records thus obtained is often dependent upon the type of material in which the explosive is detonated and that the effectiveness of a given charge of explosive is also dependent upon the material in which it is planted. Because of this dependence, it is difficult to obtain satisfactory 10 records in certain areas. For example, in many areas in which it is desired to make a seismic survey, the material at or near the surface of the earth is sandy in nature. When shot holes are dug in such material, it is necessary to use relatively large charges of explosive to obtain usable 15 records. Furthermore, the records are quite often unsatisfactory because the presence of sand about the shot hole has a deleterious effect upon the character of the wave produced by the explosion 20 of the charge.

An object of this invention is to largely eliminate the effects above referred to.

In the practice of the method of this invention, a shot hole is bored in the usual fashion. A material different from that naturally surrounding the hole is introduced into the bottom of the hole and a new hole is drilled in such material. The explosive charge is thus introduced 35 into the new hole and detonated to produce seismic waves for recording in the customary manner. Preferably, the bottom of the shot hole 40 is enlarged before introduction thereto of material different from that naturally surrounding the hole. Such enlargement of the bottom of the hole may be effected by lowering a charge of explosive to the bottom of the hole and detonating it in order to produce a cavity.

The type of material chosen for introduction into the cavity is determined both by the character of the natural material in which the hole is dug and by the type of results which are desired. In the specific case previously mentioned, if a shot hole is dug in sand any one of several materials may be introduced into the cavity. A satisfactory material consists of a mixture of rapid hardening Portland cement and bentonite. 50 Another suitable material is a mixture of clay

and water such as is commonly used in drilling oil wells by the rotary drill method. Such material is preferably introduced in sufficient quantity to entirely fill the cavity at the bottom of the hole and to extend some distance up the hole. After the introduced material has hardened or 5 sufficiently solidified by settling, a new hole is drilled therein.

Referring now to the drawing wherein the single figure diagrammatically illustrates a bore hole 10 made according to the invention, the upper portion of the original bore hole is designated by the reference character 10a. The lower portion 10b of the bore hole is drilled into material 11 introduced into a cavity formed at the bottom of 15 the drill hole. This material is different than the material in which the cavity is made and preferably is of greater density and greater compactness than the material in which the cavity is formed. The explosive charge 12 is then lowered 20 to the bottom of the bore hole and is detonated in the usual manner by means of the firing mechanism 13.

It often happens that the shot hole is dug into a limestone which is badly shattered and creviced. 25 In such event, the materials previously mentioned may be introduced into the bottom of the hole to form a compact mass into which the bore hole is extended as above described.

In some cases, where the shot hole is formed 30 in earth of greater density than sand, it may be desirable to alter the character of the wave front produced by the detonation of an explosive charge so as to reduce the percentage of energy contained 35 in the higher frequency components. Such alteration in the wave front may be produced by using sand or similar granular material to fill the cavity at the bottom of the shot hole. In any use of the method, material of different composition than the material in which the bore hole is 40 made is introduced into the bottom of the bore hole and a new hole is made in such material in which the explosive charge is arranged and detonated. Preferably, the bottom of the bore hole 45 is first enlarged to form a cavity within which is received the material of different composition than the material of which the cavity is made, but in some instances, particularly when a small charge of explosive is to be used, it may not be necessary to form a cavity at the bottom 50 of the hole and in such a case, the material is introduced into the bottom of the original hole and a new hole of smaller diameter is drilled in the introduced material. The words "solid ma- 55 terial" are used in the claims to define any ma-

terial of sufficient stability to permit a hole being formed therein and are intended to cover plastic material as well as rigid material.

I claim:

- 5 1. The method of creating artificial seismic waves for use in sub-surface surveying which comprises conditioning a shot hole formed in sandy soil by forming a cavity at the bottom of the hole, introducing into the cavity a mixture 10 of quick-hardening cement and bentonite, extending the shot hole into the introduced material and detonating an explosive charge in the extension of said hole.
- 15 2. The method of creating artificial seismic waves for use in sub-surface surveying which comprises drilling a hole, filling the lower portion of said hole with solid material different from that in which the hole is drilled, drilling a hole in the filled-in material and detonating an explosive charge in said last-named hole.
- 20 3. The method of creating artificial seismic waves for use in seismic surveying which comprises drilling a hole, filling the lower portion of said hole with solid material different from that 25 in which the hole is drilled, drilling in the filled-in material a hole of smaller diameter than the original hole and detonating an explosive charge in said smaller diameter hole.
- 30 4. The method of creating artificial seismic waves for use in sub-surface surveying which comprises conditioning shot holes formed in the earth by filling the lower portion of the hole with solid material different than the earth in which the hole is formed, drilling a new hole in such 35 material, and detonating an explosive charge in said new hole.
- 35 5. The method of creating artificial seismic waves for use in sub-surface surveying which comprises drilling a hole, enlarging the bottom 40 of the hole, filling the enlargement with solid

material different from the material in which the enlargement is made, extending the hole into the filled-in material and detonating an explosive charge in the extension of said hole.

6. The method of creating artificial seismic waves for use in sub-surface surveying which comprises drilling a hole, enlarging the bottom of the hole, filling such enlargement with solid material of greater density than the material in which the enlargement is made, extending 10 the hole into the filled-in material and detonating an explosive charge in the extension of said hole.

7. The method of creating artificial seismic waves for use in sub-surface surveying which 15 comprises drilling a hole, enlarging the bottom of the hole, filling the enlargement with solid material of greater compactness than the material of which the enlargement is made, extending 20 the hole into the filled-in material, and detonating an explosive charge in the extension of said hole.

8. The method of creating artificial seismic waves for use in sub-surface surveying which comprises conditioning shot holes formed in 25 sandy earth by enlarging the bottom of the hole, filling the enlargement with solid material of greater density than the earth in which the hole is formed, extending the hole into the filled-in material and detonating an explosive charge in 30 the extension of said hole.

9. The method of creating artificial seismic waves for use in sub-surface surveying which comprises drilling a hole in the earth, filling the lower portion of the hole with a mixture of quick 35 hardening cement and bentonite, extending the shot hole into the introduced material and detonating an explosive charge in the extension of said hole.
